* cited by examiner

Primary Examiner — Lakiya G Rogers*Assistant Examiner* — Harold E Blackwell, II(74) Attorney, Agent, or Firm — Cantor Colburn LLP(57) CLAIM

The ornamental design for a handle for a home appliance, as shown and described.

DESCRIPTION

FIG. 1 is a front perspective view of a handle for a home appliance showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is the rear perspective view thereof.

The broken lines illustrating portions of the handle for a home appliance form no part of the claimed design.
